UNITED STATES PATENT OFFICE.

JOSEPH J. KLOSTERMAN, OF DAYTON, OHIO, ASSIGNOR TO THE NATIONAL CASH REGISTER COMPANY, OF DAYTON, OHIO, A CORPORATION OF MARYLAND.

CASH REGISTER.

Application filed June 14, 1926. Serial No. 115,910.

This invention relates to improvements in transfer mechanism of the type shown and described in Letters Patent of the United States No. 497,860, issued to Thomas Carney, dated May 23, 1893.

The object of this invention is to provide an improved transfer mechanism which cannot be tripped prematurely, thereby causing transfers to be made at the wrong time.

With this and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a cross-section through the machine showing a type of machine to which the invention is applied.

Fig. 2 is a detail view of the mechanism for rotating the main cam shaft.

Fig. 3 is a detail view of the transfer mechanism shown in its untripped position and with the totalizer element standing at nine.

Fig. 4 is a detail view of the transfer mechanism shown in the position which it assumes just before the totalizer element reaches zero.

Fig. 5 is a detail view of the transfer mechanism shown in the position it assumes when the totalizer element reaches zero.

Fig. 6 is a section through the totalizer showing the transfer carrying pawl in its moved position after the transfer mechanism has been tripped, the lower totalizer element being shown in the "one" position.

Fig. 7 is a top plan view of the totalizer.

Fig. 8 is a detail view of the transfer mechanism showing the carrying pawl moved forward and the relation of the transfer tripping and restoring pawls thereto when the totalizer element is standing at zero.

In general.

The machine to which the invention is shown applied is of a well known key operated type, in which the depression of a key itself performs all of the adding and printing operations of the machine. In transfer mechanisms of the type shown herein it is possible, by operating the machine too fast, to cause the transfer pawl to be tripped by overthrowing the totalizer element when it is

supposed to stop at "nine". Upon operation of the machine, with the transfer pawl thus tripped, transfers take place when no transfer is desired. In the present application the trip pawl is so timed that it will not trip the carrying pawl until the totalizer element actually reaches its zero position. In the totalizer to which the invention is shown applied, it is necessary to provide a second pawl for restoring the transfer carrying pawl to its normal position during the operation of the machine.

In detail.

The machine is provided with a plurality of groups of amount keys 30 pivoted on a rod 31, and each key carries an upright 32. Each group of uprights is adapted to differentially operate a frame 33, to which is secured an actuator segment 34. The totalizer pinions 35 are adapted to be engaged with the respective segments 34, before the segments are actuated, by means of a cam 36 secured on a main cam shaft 37 which cooperates with an arm 38 for rocking a totalizer frame 39. A totalizer of the type shown and described in the application for letters patent of the United States by Edward J. Von Pein, Serial No. 87,348, filed February 10, 1926 has been shown because the type wheel 41, which is driven by a gear 40 secured to the totalizer pinion 35, sets up additional momentum, thereby increasing the possibility of overthrowing the totalizer element. However, it is to be understood that this improvement is not restricted to this totalizer inasmuch as it can be used in connection with any totalizer where the transfer mechanism is of the type herein shown and described, such as for example as shown in the above mentioned Carney patent.

The cam shaft 37 is given one complete rotation during each operation of the machine by means of the well known double faced rack 45 which is adapted to mesh with a pinion 46 secured to the shaft 37. A key coupler 47 is provided for coupling the keys of the various denominations together when they are operated, and also for returning the keys to their home position. This key coupler is provided with a roller 48 (Fig. 2), which engages a slot in a rack 45 and thereby raises and lowers the rack once during each operation of the machine. All of the above mechanism is old and well known in the art.

and therefore no further description thereof will be given.

Transfer mechanism.

- 5 Each totalizer element is provided with a single toothed member 55 (Figs. 3, 4, 5 and 8) which is adapted to engage a nose 56 of a restoring pawl 57, as the totalizer element moves from nine to zero. As the 10 totalizer element reaches its zero position, it engages the nose 58 of a trip pawl 59, thereby rocking it in a counter-clockwise direction. The restoring pawl 57 is provided with a shoulder which normally prevents 15 a carrying pawl 61 from being rocked into its effective position. Each pawl 61 is provided with a spring 62 which tends to rock the pawls to their effective positions. The carrying pawls are pivoted on arms 63 which arms are operated by cams 64 on the cam shaft 37. The cams 64 are arranged spirally on the cam shaft so that the transfers are successively entered. When any 20 transfer arm 63 is operated, after its cooperating carrying pawl 61 has been tripped, it will engage a ratchet 65 secured to the totalizer element of the next higher order, thereby causing one to be added therein.

By referring to Fig. 3 it can be seen that 30 the single toothed member 55 will engage the nose 56 of the pawl 57 before it engages the nose 58 of the trip pawl 59. Fig. 4 shows the member 55 after it has rocked the restoring pawl 57 from engagement with the flange 60, and in a position where it is about to rock the trip pawl 59. The trip pawl 59 is provided with a shoulder which is slightly lower than the shoulder on the restoring pawl and, therefore when the restoring pawl is rocked from engagement with the flange 60 of the carrying pawl, the flange 60 will drop into engagement with the shoulder on the trip pawl 59. This is the 40 position of the parts just before the totalizer element reaches its zero position. Fig. 5 shows the carrying pawl 61 tripped, and the totalizer element in its zero position. As the carrying pawl moves forward a spring 66 will cause the restoring pawl 57 to follow, as shown in Fig. 8, until the shoulder thereon is again beneath the flange 60 of the carrying pawl. When the carrying pawl is returned to its normal position, the flange 60 will again engage the shoulder of the 50 restoring pawl. The restoring pawl 57 is required because the trip pawl 59 is so formed that the member 55 prevents the trip pawl from following the carrying pawl, as shown in Figs. 6 and 8, far enough to cause it to be returned home.

The shoulder on the trip pawl is lower than the shoulder on the restoring pawl for two reasons. First, when a transfer is effected and the carrying pawl is returned toward its home position, if the shoulders

were both the same height there would be a possibility of the flange 60 striking the rear face of the trip pawl thereby moving it counter-clockwise, and therefore the trip pawl would not be effective during the next transfer operation. This possibility is eliminated because the restoring pawl will hold the flange 60 high enough, during this return movement, to prevent such engagement. Second, when the totalizer element stops at zero the member 55 holds the trip pawl in its extreme forward position. When the transfer is made, by moving the carrying pawl 61, the restoring pawl moves forward and it then returns to home with the carrying pawl. After these two pawls return home, the trip pawl is still maintained in its extreme position. When thus held and an amount is added into the element the tooth of the member 55 passes from contact with the trip pawl and then the spring 67, causes the trip pawl to rock toward its normal position. Under this circumstance if the shoulder of the trip pawl was not lower it could not move below the flange 60 and therefore it would remain ineffective.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. In a transfer mechanism, the combination of a totalizer element, a carrying pawl, a trip pawl, a restoring pawl for the carrying pawl, and means for tripping the trip pawl and the restoring pawl, said trip pawl being adapted to be tripped as the totalizer element reaches its zero position and the restoring pawl being adapted to be tripped prior to the trip pawl.

2. In a transfer mechanism, the combination of a totalizer element, a carrying pawl, means for causing the carrying pawl to be tripped as the totalizer element reaches zero, a restoring pawl for said carrying pawl adapted to normally engage said carrying pawl and to be tripped prior to the tripping of said carrying pawl by said means, and means for operating said carrying pawl for effecting a carry, said restoring pawl being adapted to move with said carrying pawl for the purpose of returning the carrying pawl into engagement with said trip pawl.

3. In a transfer mechanism, the combination of a totalizer element, a carrying pawl, a trip pawl, a restoring pawl, means for tripping the trip pawl and the restoring pawl as the element moves from nine to zero, and means for operating said carrying pawl for effecting a carry, said restoring pawl

being adapted to move with said carrying pawl for the purpose of returning the carrying pawl into engagement with said trip pawl.

5 4. In a transfer mechanism, the combination of a totalizer element, a carrying pawl, a trip pawl, a restoring pawl, means for tripping the trip pawl and the restoring pawl, a projection on said trip pawl for holding the trip pawl disengaged from the

carrying pawl after the carrying pawl has been tripped, and a projection on said restoring pawl formed so as to permit the restoring pawl to be tripped and to permit the restoring pawl to move with the carrying pawl 15 for restoring the carrying pawl into engagement with the trip pawl.

In testimony whereof I affix my signature.

JOSEPH J. KLOSTERMAN.
